United States Patent

Des. 238,863

Patented Feb. 17, 1976

238,863

SAILBOAT

Hobart L. Alter, Capistrano Beach, Calif., assignor to
Coast Catamaran Corporation

Filed May 28, 1974, Ser. No. 473,911

Term of patent 14 years

Int. Cl. D12—06
U.S. Cl. D12—64

FIG. 1

FIG. 2

FIG. 3

FIG. 4

FIG. 5

FIG. 6

FIG. 7

FIG. 8

FIG. 1 is a perspective view of a sailboat showing my new design;

FIG. 2 is a side elevational view of said sailboat, the side opposite that shown being identical;

FIG. 3 is a front view of said sailboat;

FIG. 4 is a rear view of said sailboat;

FIG. 5 is a top elevational view of said sailboat;

FIG. 6 is a bottom view of said sailboat;

FIG. 7 is a vertical sectional view taken on line 7-7 of FIG. 2, with the daggerboard omitted for convenience of illustration; and

FIG. 8 is a vertical sectional view taken on line 8-8 of FIG. 2.

I claim:

The ornamental design for a sailboat, substantially as shown and described.
